UNITED STATES PATENT OFFICE.

FRANK BUSSIERE, OF ESSEXVILLE, MICHIGAN, ASSIGNOR TO HARRISON W. GARLAND, OF BAY CITY, MICHIGAN.

SEWING MACHINE.

Application filed June 19, 1920, Serial No. 390,283. Renewed April 30, 1923.

To all whom it may concern:

Be it known that I, FRANK BUSSIERE, a citizen of the United States of America, residing at Essexville, in the county of Bay 5 and State of Michigan, have invented certain new and useful Improvements in Sewing Machines, of which the following is a specification.

This invention relates to improvements in 10 hand operated sewing machines and the like.

One object of the invention is to provide a hand operated sewing machine of a size which can be conveniently carried in the pocket, or packed in a traveling bag.

15 A further object is to design a sewing machine for quickly mending rents in clothing or the like when traveling, or in the field.

A still further object is to design a hand 20 operated sewing machine by means of which tents, blankets or other articles requiring considerable sewing can be quickly sewed, eliminating the use of the hand operated needle and thread, and without bringing the material to the usual sewing machine generally used for such purposes.

With the above and other objects in view, the present invention consists in the combination and arrangement of the different parts, hereinafter more fully described, illustrated in the accompanying drawings, and more particularly pointed out in the appended claims, it being understood that changes may be made in the form, size, and proportion of the different parts without departing from the spirit of sacrificing any of the advantages of the invention.

In the drawings:—

Figure 1 is a front view of my improved sewing machine, and

40 Figure 2 is a side view thereof.

Figure 3 is a top plan view, and

Figure 4 is a detail of the spool spindle.

Figure 5 is an enlarged rear view of the operating mechanism with the outer casing 45 removed.

Figure 6 is a side view thereof, and

Figure 7 is an inverted plan of Figure 5.

Figure 8 is an enlarged inverted plan of the pressure bar.

50 Figure 9 is a sectional view taken on the line 9—9 of Figure 5.

Figure 10 is a view showing the needle in raised position.

Figure 11 illustrates the needle at the end 55 of its downward stroke.

Figure 12 illustrates the needle in position when the stroke is complete, the dotted lines showing the position of the different parts when the needle is being raised.

Figure 13 is a detail showing the position 60 of the thread in the needle when it has pierced the cloth.

Figure 14 is a detail showing the loop 65 formed by the thread when needle is in the position shown in dotted lines in Fig. 12.

Figure 15 is an enlarged view illustrating the stitches on the underside of the cloth, the needle being shown in section.

Referring now more particularly to the drawings in which I have designated the 70 outer casing of the machine by the numeral 1, the upper portion of which is adapted to be closed by means of a cover 2, hinged thereto in any suitable manner to allow the spool of thread to be inserted in the case, the 75 bottom of the case is open, a pressure bar extending therethrough in a manner to be hereinafter more fully described.

Secured to the interior of the case member 1 is a plate 3, this plate being bent as 80 shown in Figures 5 and 6 to form a closure for the bottom of the case, it is further provided with an opening 4, through which the pressure bar 5 is adapted to extend, a small 85 pinion member 6 being mounted on a shaft member 6^a which is journaled to the plate 3, a crank member 7 is also rigidly seated on this shaft 6^a one end thereof being pivoted to the connecting link 8 at the point 9, the 90 opposite end of the link being in turn pivoted to a cross head 11 at the point 12, the cross head being grooved as shown at 12^a, in Fig. 9, to fit the edges of the plate member 3, which is formed to receive same, an ordinary 95 sewing machine needle is inserted in the opening in the cross head 11, and is secured in position by means of a small set screw 13, on which is also mounted a pair of small washers or annular members 14, between which the thread is adapted to travel.

An operating handle 15 is pivoted to the plate 3 at the point 16, the forked portion 15^a extending beyond the case and is designed to fit the fingers of the operator. The inwardly extending portion is formed 105 with a plurality of teeth 17 on the inner surface thereof which are adapted to mesh with the pinion 6, a coiled spring member 18 being secured to the handle and to the plate 3, and it will be obvious that as the operating 110

handle is forced to the position shown in dotted lines in Fig. 5, that the pinion 6 will be rotated and the connecting rod and crank will assume the position shown in dotted

5 lines, the spring will be stretched, and the needle will have pierced the material to be sewed and be returned to its original position, the operator then releases the operating handle and the tension of the spring 18 10 will force the several members back to their original position as shown in full lines in Fig. 5, thereby completing another full stroke with the needle.

A pressure bar 5 is slidably mounted on 15 the plate member 3, said plate being punched to form guides or keepers 19 between which the said pressure bar is slidably held, the upper end of the bar is bent as shown at 20 and extends through the walls 20 of the case to form a thumb rest, the bar extends downwardly being bent as shown at the point 21, and having a coiled expansion spring 22 interposed between the bar and the plate member 3, thence the bar extends 25 below the bottom of the case, thence up and having a flat portion 23 over which the cloth or material to be sewed is adapted to feed, the ends of the said flattened portion being bent downwardly so that they will not 30 catch in the cloth or other material.

A pinion member 24 is mounted on the shaft 25, one end being journaled in the wall of the plate, the opposite end being journaled in the upwardly bent lug 26, a suitable opening being provided in the plate 3 through which said pinion is adapted to extend for forcing the cloth or material across the face of the pressure bar.

The pinion member 24 is adapted to be 40 rotated by means of a spring tensioned ratchet arm 27, slidably secured to the plate 3 by means of the member 29, extending through the slotted opening 28, the upper end of the said arm extending inwardly and into the path of the cross head 11, a spring member 30 being anchored to the said ratchet arm and to the plate member 3, and it will be obvious that as the cross head oscillates up and down it will strike the inwardly extending portion of the said arm 27 on its upward stroke, raising the said arm and rotating the pinion member 24 for feeding the cloth or material across the face of the pressure bar, the spring member 30 drawing the ratchet bar down for again engaging the teeth of the pinion.

The length of stitch is regulated by 60 means of the cam lever 31 pivoted to the plate 3 at the point 32, the lower end of said lever being bent outwardly and extends through a suitable opening provided in the case 1, so that the said lever can be readily operated, the upper end of this lever is cam shaped and by turning the said lever it will 65 be readily understood that the length of

travel of the said ratchet arm and consequently the travel of the material across the face of the pressure bar can be accurately regulated.

I wish to call particular attention to the 70 fact that the ordinary sized spool of thread can be employed, the spindle being indicated by the numeral 33, and clearly shown in Fig. 4 of the drawings, and in the present instance I have shown this spindle 75 formed of one piece of material, the ends 34 being pivoted in the walls of the case, the spindle being swung upwardly and the spool placed in position, the spindle is then 80 swung down to horizontal position, the end thereof entering a slot in the end of the case, the thread extends through a slotted opening 35 beneath the lip of the cover, thence in under the portions 36 formed on the case, and between the members 14, thence 85 being threaded into the needle 37.

The machine is designed for so called 90 single stitching, and in Figures 10 to 14 I show the different positions of the thread and the several parts, Figure 10 illustrates 95 the needle in raised position, the ratchet having rotated the pinion for moving the cloth or material 38 across the face of the pressure bar, Figure 11 illustrates the position of the needle when the stroke is one 100 half completed, with the ratchet in lower position for again engaging the teeth of pinion 24, Figure 12 is a view showing in dotted lines the stroke three quarters completed and in solid lines, the position at the 105 end of the stroke, and Figure 13 shows the position of the thread when the needle has pierced the cloth; Figure 14, illustrates the thread looped when the needle is withdrawn, while Figure 15 is an enlarged view 110 of the stitches, and it will be obvious that the position of the cam lever determines the length of the stitches by regulating the movement of the ratchet member 27 which rotates the pinion for feeding the cloth over 115 the face of the pressure bar.

I further wish to call attention to the 120 groove 38 which is formed in the bottom of the plate 3 directly in line with the opening 39 through which the needle travels, and when the needle travels the ratchet member rotates the pinion 24 pulling the cloth forward, the thread forming a loop as shown in Figure 14, and when the needle is in the position as shown in dotted lines in Figure 12, the loop is drawn flat against the pressure bar in under the cloth, and the thread from the eye of the needle will be drawn along the groove 38 and it will have 125 no frictional resistance, but the upward pull of the spring 22 on the pressure bar will maintain a frictional resistance on the loop below the cloth, so that all slack in the thread will be taken up in each succeeding 130 stitch, the downward movement of the

needle passes through this loop and completes the single stitch shown in Figure 15.

For placing the material to be sewed in proper position it is merely necessary for 5 the operator to press downwardly on the portion 20 of the pressure bar thereby forcing the face of the pressure bar away from the pinion 24 a distance sufficient to allow 10 the cloth to be placed in position, the body 15 of the case is then placed in position in the palm of the hand, and the fingers engage the handle 15 for operating the machine.

From the foregoing description it will be 15 obvious that I have perfected a simple and economical sewing machine which can be conveniently carried in the pockets of the operator's garments.

What is claimed is:

1. A hand operated sewing machine comprising a vertically disposed plate, a cross head carried for reciprocating movement thereby, a needle removably received in said cross head, a link connected to said cross head, a crank in turning engagement with 25 said link, a pinion adapted to turn said crank, an actuating lever having a portion thereof arranged to fit the hand of the operator and provided with a gear segment meshing with said pinion, yieldable means 30 for holding said lever in an initial position, and means for supporting and feeding the cloth past said needle.

2. A hand operated sewing machine comprising a vertically disposed plate, a cross head mounted to reciprocate vertically on 35 said plate, means for reciprocating such cross head, a needle carried by said cross

head, a pressure plate resiliently supported from said vertical plate and adapted to hold the cloth in the path of said needle, a toothed wheel having engagement with the cloth for feeding the same over said pressure plate, a pawl yieldingly held in an initial position and having engagement with the teeth of said wheel, means whereby said pawl may be reciprocated in accompaniment to the movement of said cross head, and means for regulating the degree of the movement of said pawl.

3. A hand operated sewing machine comprising a vertically disposed plate, a casing enclosing said plate, a hinged spindle in said casing adapted to receive a spool of thread, a reciprocating needle support mounted on said plate within the casing, a pressure bar resiliently supported from said plate beneath the casing, and means for feeding the cloth over said pressure bar.

4. A hand operated sewing machine comprising a vertically disposed plate, a casing 60 removably surrounding said plate and having a hinged top, a hinged spindle in said casing having a portion projecting beyond the casing for receiving a spool of thread, a reciprocating cross head in said casing, 65 means to reciprocate said cross head, a needle removably carried by said cross head, a resiliently supported pressure bar extending beneath said casing, and means for feeding the cloth automatically across said pressure bar.

In testimony whereof I affix my signature.

FRANK BUSSIERE.
